DESIGN FOR A TABLE SCARF OR SIMILAR ARTICLE

Ruth C. Oppenheim, New York, N. Y.

Application January 20, 1943, Serial No. 109,294

Term of patent 3½ years

To all whom it may concern:

Be it known that I, Ruth C. Oppenheim, a citizen of the United States, residing at Manhattan, county of New York, and State of New York, have invented a new, original and ornamental Design for a Table Scarf or Similar Article, of which the following is a specification, reference being had to the accompanying drawing, forming part thereof, wherein the figure is a plan view of a portion of a table scarf showing my new design. A full repeat unit is shown, said unit being repeated downwardly, as indicated in the figure, to form a complete scarf.

I claim:

The ornamental design for a table scarf or similar article, as shown and described.

RUTH C. OPPENHEIM.
